(57) CLAIM

I claim the ornamental design for a massaging tool, as shown and described.

DESCRIPTION

FIG. 1 is a left side elevational view of the design;
FIG. 2 is a right side view of the design;
FIG. 3 is a front elevational view of the design;
FIG. 4 is a rear elevational view of the design;
FIG. 5 is a top plan view thereof; and,
FIG. 6 is a bottom view thereof.
